UNITED STATES PATENT OFFICE

EARL C. BOOTH, OF COLUMBUS, INDIANA, ASSIGNOR TO NOBLITT-SPARKS INDUSTRIES, INC., OF COLUMBUS, INDIANA, A CORPORATION OF INDIANA

DESIGN FOR AN AUTOMOBILE-RADIO CONTROL UNIT

Application filed May 22, 1933. Serial No. 48,177. Term of patent 7 years.

To all whom it may concern:

Be it known that I, EARL C. BOOTH, a citizen of the United States, residing at Columbus, Bartholomew County, Indiana, have invented a new, original, and ornamental Design for Automobile-Radio Control Unit, of which the following is a specification, reference being had to the accompanying drawing, forming part thereof.

Fig. 1 is a plan view of a control unit embodying my new design, and

Figs. 2 and 3 are end and side elevations respectively of such control unit.

I claim:

The ornamental design for an automobile-radio control unit, as shown.

In witness whereof, I have hereunto set my hand.

EARL C. BOOTH.
